BEAM ANTENNA SYSTEM

Burton P. Brown, Jr., Scotia, N. Y., assignor to
 General Electric Company, a corporation of
 New York

Application May 4, 1943, Serial No. 485,601

7 Claims. (Cl. 250—33.65)

1

This invention relates to antenna systems and more particularly to antenna systems adapted for radiating sharply directive beams of radio frequency energy.

Systems have been proposed in which periodic pulses of short wave oscillations have been radiated into space and an echo of each pulse has been received in the period prior to the next succeeding pulse. In communication systems of this type there have been provided antenna systems from which are radiated periodic pulses and by which the echoes are intercepted. Antenna systems for such purposes are usually of a type projecting a sharp beam of radio energy into space and are usually provided with a reflector which may be of any suitable surface of revolution but are most commonly of paraboloid form. The beam is projected at a small angle to the axis of the reflector and the radiator is located on the axis at substantially the focal point of the reflector in order to rotate the beam about the surface of a cone, the axis of which is the axis of the reflector. The radiating system including the reflector is arranged to be oriented both in elevation and in azimuth by suitable mechanical means so that the axis of the paraboloid can be directed at a remote object such as a target and maintained so oriented.

Such systems have been generally described and claimed in application Serial No. 482,403 to Donald E. Norgaard, filed April 9, 1943, now Patent 2,455,265, granted November 30, 1948, and application Serial No. 414,126, of Sidney Godet, filed October 8, 1942, now Patent 2,412,612, granted December 16, 1946, both of which are assigned to the same assignee as the present invention.

It is an object of my invention to provide a new and improved antenna system for such systems of communication.

It is another object of my invention to provide a search antenna for such a system which is simple in form, easy of manufacture and assembly, relatively inexpensive, and so arranged that the radiating parts are not subject to any appreciable centrifugal force.

The features of my invention which I believe to be novel are set forth with particularity in the appended claims. My invention itself, both as to its organization and manner of operation, together with further objects and advantages thereof may best be understood by reference to the following description taken in connection with the accompanying drawing in which Fig. 1 is a partial, plan view of an antenna system embodying the principles of my invention; Fig. 2 is a sectional side elevational view of the appa-

2

ratus shown in Fig. 1; and Fig. 3 is an enlarged view of the antenna element and associated reflector element shown in Figs. 1 and 2.

In the accompanying drawing there is shown 5 an antenna system comprising a paraboloid reflector 10, an antenna member 11, and a reflector member 12. The antenna member 11 is of the dipole type including collinear elements 13 and 14. The dipole is located at or near the focus 10 of the paraboloid reflector and the axis of the reflector 10 passes through the dipole at or near the midpoint thereof. While there is illustrated a reflector element 12, it will be understood that the element 12 may be omitted, if desired. However, the reflector element 12 reflects energy radiated outwardly from the antenna element 11 into the paraboloid reflector 10 so that a sharper beam results when the reflector element 12 is used.

20 Means is provided for exciting the antenna element 11. This means comprises a source of signal energy which may be considered to be included in the box indicated by numeral 15, an open transmission line 16 and a concentric transmission line 17, the latter comprising an inner conductor 18, represented by the dotted lines in Fig. 2, and an outer cylindrical conductor or tube 19 through which the inner conductor extends. The inner conductor extends along the axis of the paraboloid.

25 The source of signal energy or transmitter contained within the box 15 produces pulses of oscillations of high frequency energy and supplies them to the transmission line 16. The pulses are transferred to the concentric transmission line section 17 through a suitable type of rotating joint, indicated by the numeral 20. The antenna array comprising the elements 11 and 12 also receives echo pulses and supplies them to a suitable pulse receiver which may also be considered to be contained within the box 15.

30 Means is provided for shifting the antenna beam pattern from coincidence with the axis of the reflector and for rotating the antenna assembly so that a rotating beam will be projected. In the illustrative form of my invention, the dipole is tilted, that is, disposed at an angle of other than 90°, with respect to the axis of the paraboloid reflector. This arrangement causes the projecting beam to have an angle of a few degrees with respect to the paraboloid axis. The beam shift may be increased further by unbalancing the currents in the antenna elements 13 and 14. It is well known that in order to have balanced current in the arms or elements of a dipole when those arms or elements are of equal length, a

cylinder of approximately one-quarter wave length may be attached to the end of a concentric transmission line used for exciting the dipole, the cylinder being concentrically disposed with and surrounding the transmission line, open at the radiating end of the line, and attached to the outer conductor of the line at the other end. In the form of my invention described herein no such line balancing arrangement is employed so that the means for conducting the energy to be radiated from the transmission line 16 to the antenna member 14 consists only of the concentric transmission line 17 and the radiating joint 20. Omission of the line balancing cylinder thus causes further beam shift. If still additional beam shift is required the arms or elements 13 and 14 of the antenna member 11 may be made of different lengths, as shown in the drawing.

In order to permit the determination of the elevation and azimuth of the object from which echoes are received, it is desirable to rotate the displaced pattern about the axis of the paraboloid reflector. For this purpose there is provided a suitable motor 21 receiving electrical energy from a suitable source, not shown, and carried by the base plate 36 attached to the paraboloid reflector in any suitable manner. The motor is operatively connected to the outer conductor 19 through suitable gears 22 and 23 carried by the shaft of the motor and the outer conductor or tube 19 respectively. The rotation producing means and the transmission line 17 are mounted as shown at the center of the paraboloid reflector. Because of the mechanical couple resulting from the unbalanced disposition of the dipole, there results a tendency of the parts of the antenna assembly to "whip" during rotation. In order to minimize the effects of centrifugal force, the transmission line section 17 is supported as close as practicable to the dipole. For this purpose there has been provided a conically shaped support 25 located at the center of the paraboloid reflector and attached to the base 36 at the large end. Suitable bearing means 26 is provided at the small end of the cone. If desired, a bearing may also be provided where transmission line 17 passes through the supporting structure. At any rate, the transmission line section 17 is preferably supported at two points, although some additional support is provided through the intermeshing gears. It will be noted further that the conical member 25 and the base plate 36 serve as a housing for the gears.

In order to obtain intelligence which may be employed to cause the antenna system, including the paraboloid reflector, to follow the target or source of echo, there has been shown a two-phase alternator 28 suitably carried by the paraboloid reflector as on the base plate 36, and caused to rotate by means of a suitable gear 29 attached to the shaft of the alternator and meshing with the pinion or gear 23. The output of the alternator is utilized to energize suitable elevation and azimuth controlling mechanism in the manner described in the above identified copending applications.

As shown in Fig. 3, means is provided for connecting the elements 13 and 14 of the antenna member 11 to the transmission line members 18 and 19. The shorter member 14 may be connected directly to the outer conductor 19 in any desired fashion, as by welding, for example. Means is provided for passing the longer element 13 through an opening in the outer conductor 19 into engagement with the inner conductor 18 and

for securing the element 13 to the outer conductor in such a manner as to lend support to the inner conductor and to maintain that conductor fixed with respect to the outer conductor during rotation of the apparatus thereby minimizing the effects of centrifugal force on the inner conductor and the reflecting member 12. The means connecting the elements 13 and the outer conductor 19, of course, is electrically insulative. In the form of my invention illustrated herein, this purpose is accomplished by providing a stud 30 having a threaded laterally extending portion 31 adapted to engage the threads of a suitably tapped bore in the end of the arm 13. An insulating member 32 is retained at the opening in the outer member 19 between the stud 30 and the end of the arm 13. For example, the cage of the member 32 may be suitably secured to a metal washer 32a and the outer edge of the member or washer 32a may be engaged by a flanged member 33 having internal threads engaging suitable threads in the outer surface of the washer 32a. The inner end of the stud 30 is securely fastened to the inner conductor 18 as by means of a suitably threaded fastening member 34 passing through a suitable opening in the conductor 18 into suitable threaded engagement with the bore in the stud 30. The arm 13 is shown bent at the inner end thereof in order to approach the inner conductor at right angles thereto for convenience of assembly. With this arrangement, the stud may be fastened in position, the insulative washer applied over the lateral portion 31 of the stud 30 and the flanged member 33 fastened in place. The arm 13 may then be screwed onto the lateral portion 31 of the stud. The reflector member 12 may be secured to the end of the inner conductor 18 in any suitable manner as by means of the threaded fastening member 35.

The above described means for supporting the antenna system and associated parts is not my invention but is disclosed and claimed in a copending application of C. L. Rouault, application Serial No. 483,555, filed April 19, 1943, now Patent 2,446,436, granted August 3, 1948, and assigned to the same assignee as the present invention.

A system embodying the above principle has been constructed for operation at approximately 400 megacycles. The dipole was tilted 13° with respect to a plane perpendicular to the axis of the paraboloid reflector. The antenna members 11 and 12 were each approximately one-half wave length long and spaced apart at their centers approximately one-quarter wave length. The reflector element was one inch in diameter and seventeen inches long. The antenna elements 13 and 14 were also one inch in diameter and the longer arm 13 was seven and a half inches long while the shorter arm 14 was six inches long. The tube 19 was one and five-eighths of an inch in diameter and the paraboloid reflector was seven feet in diameter. The antenna members 11 and 12 were rotated at 1800 R. P. M. With such an arrangement a beam shift or angle with respect to the axis of the paraboloid reflector of the order of 3½° to 4° was obtained. Of this shift, the omission of the concentric matching cylinder was found to be accountable for approximately 2° to 3°, and the arrangement of the antenna member 11 was responsible for the remaining 2°. If the arms 13 and 14 were of equal length, slightly less than 2°, benefit was obtained by tilting the dipole. The amount of tilt of the dipole has an important effect on the beam shift. Thus if the dipole

is at right angles with respect to the axis of the paraboloid reflector there is no shifting of the beam. As the tilt is increased the beam shift is increased, but inasmuch as the mechanical force tending to cause "whipping" of the rotating parts increases rapidly as the angle of tilt increases, there are mechanical limitations to the amount of tilting permissible.

The reflector may comprise any desired reflecting surface. However, in order to minimize wind pressures on the reflector, it is preferable to form the paraboloid reflector 10 in the form of a mesh, as by means of wires or rods as, for example, a plurality of concentric rings connected to radially extending members as shown in Figs. 1 and 2. In the above specific example the spacing between the members was approximately four inches.

While I have shown and described a particular embodiment of my invention, it will be obvious to those skilled in the art that changes and modifications may be made without departing from my invention in its broader aspects, and I therefore aim in the appended claims to cover all such changes and modifications as fall within the true spirit and scope of my invention.

What I claim as new and desire to secure by Letters Patent of the United States is:

1. In an antenna system comprising a reflector having a directive axis, a directive antenna member located on the directive axis of said reflector at substantially the focus thereof, said member comprising a transverse dipole tilted at an angle other than 90° with respect to said axis whereby the beam radiated from said antenna member is at an angle with respect to said axis, means for exciting said antenna member, and means for rotating said antenna member on said axis with respect to said reflector.

2. In a beam antenna system comprising a reflector having a directive axis, a directive array located on the axis of said reflector, said array comprising a linear radiator located at substantially the focus of said reflector and a reflector member also located on the axis of said reflector and arranged to reflect radiation from said radiator back to said reflector, said radiator extending transversely across said axis at an angle other than 90° thereto, means for exciting said radiator, whereby the beam radiated from said radiator is at an acute angle with respect to said axis, and means for rotating said array on said axis with respect to the reflector.

3. In a beam antenna system comprising a reflector having a directive axis, a directive array located on the axis of said reflector, said array comprising a linear radiator member located at the focus of said reflector, and a reflector member also located on the axis of said reflector and arranged to reflect radiation from said radiator back to said reflector, and means for exciting said radiator, said radiator member being positioned transversely at an angle other than 90° with respect to said axis whereby the beam radiated from said radiator is at an acute angle with respect to said axis, and means for rotating both members of said array on said axis with respect to the reflector.

4. In a beam antenna system comprising a reflector having the shape of a surface of revolution, a directive array located on the axis of said reflector and comprising a linear dipole located substantially at the focus of said reflector and a reflector member arranged to reflect radiation back to said reflector, said dipole extending

transversely across said axis at an angle other than 90° thereto, means for exciting said radiator comprising concentric conductors, the inner of said conductors extending beyond the end of the outer of said conductors, said reflector member being attached to the outer end of said inner member, the elements of said dipole being connected at their inner ends to the outer end of said outer conductor and to said inner conductor, respectively, a source of signal energy, a transmission line joining said conductors and said source, and means for rotating said conductors and said array with respect to said axis.

5. In an antenna system comprising a reflector having the shape of a surface of revolution, a directive array located on the axis of said reflector and comprising a linear dipole located with its center substantially at the focus of said reflector and a reflector member arranged to reflect radiation back to said reflector, said dipole extending transversely across said axis at an angle other than 90° thereto, means for exciting said dipole consisting of only two concentrically disposed electrically conductive members, the inner of said conductors extending beyond the end of the outer of said conductors, said reflector member being attached to the outer end of said inner member, the elements of said dipole being connected at their inner ends to the outer end of said outer conductor and to said inner conductor, respectively, a source of signal energy, a transmission line joining said conductors and said source, and means for rotating said conductors and said members with respect to said axis.

6. An antenna system comprising a paraboloid, a linear directive radiator located on the axis of said paraboloid at substantially the focus thereof, said radiator comprising a dipole tilted at an angle other than 90° with respect to said axis, having an electrical length of approximately one-half wave length and having axially aligned spaced-apart elements of different lengths lying on opposite sides of said axis, a reflector member having an electrical length of approximately one-half wave arranged to reflect radiation from the dipole back to the paraboloid, the centers of said members being spaced apart approximately one-quarter wave length, means for exciting said radiator member, and means for rotating said members on said axis with respect to said paraboloid.

7. A directive antenna system comprising a reflector having the shape of a surface of revolution, a linear dipole antenna located on the axis of said reflector at substantially the focus thereof, said dipole having two axially aligned elements lying on opposite sides of said axis and tilted at an angle other than 90° thereto, and means for exciting said dipole, said elements being of different lengths, whereby the currents in said elements when said dipole is energized are unbalanced and the beam radiated from antenna system is at an angle with respect to said axis.
